UNITED STATES PATENT OFFICE.

JAMES A. WILLARD, OF CHATTANOOGA, TENNESSEE, ASSIGNOR TO VACUUM DYEING MACHINE COMPANY, OF CHATTANOOGA, TENNESSEE, A CORPORATION OF TENNESSEE.

HOISTING APPARATUS.

SPECIFICATION forming part of Letters Patent No. 780,401, dated January 17, 1905.

Application filed August 11, 1904. Serial No. 220,404.

To all whom it may concern:

Be it known that I, JAMES A. WILLARD, a citizen of the United States, residing at Chattanooga, in the county of Hamilton and State 5 of Tennessee, have invented new and useful Improvements in Hoisting Apparatus, of which the following is a specification.

This invention relates to hoisting apparatus; and its object is to provide an apparatus of 10 such class whereby a mass of material may be elevated, transported, and dumped at any point desired.

The invention further aims to provide a hoisting apparatus particularly adapted for 15 use in removing a mass of dyed material from a dyeing-machine, transporting the mass to any point desired, and permitting of the dumping of the mass on either side of the support or carrier.

20 Although, as stated, the apparatus is particularly adapted for dyeing-machines, yet the same can be used for any purposes for which it is found applicable.

The invention further aims to construct a 25 hoisting apparatus which shall be simple in its construction, strong, durable, efficient in its use, and comparatively inexpensive to set up.

With the foregoing and other objects in 30 view the invention consists of the novel combination and arrangement of parts herein-after more specifically described, illustrated in the accompanying drawings, and particularly pointed out in the claims hereunto appended.

35 In describing the invention in detail reference is had to the accompanying drawings; forming a part of this specification, and wherein like reference characters denote corresponding parts throughout both views, and in which—

Figure 1 is an end view of one form of an 40 apparatus constructed in accordance with this invention with the support or carrier for the material attached thereto; and Fig. 2 is a side elevation of the apparatus, showing the support or carrier for the material in full and

dotted lines, the support or carrier being shown in tilted position in dotted lines.

In the drawings the elevating element of 50 the apparatus for elevating and lowering the support or carrier for the material is shown as a chain hoist; but it will be stated that the elevating element for raising and lowering the support or carrier may be of any other suitable form, such as a pneumatic, steam, or hydraulic device.

For the purpose of showing the adaptation of the invention the same is illustrated for use in connection with the vat of a dyeing-machine; but, as heretofore stated, the apparatus is adapted for whatever purpose it may be found applicable.

Referring to the drawings by reference characters, 1 denotes the vat of a dyeing-machine, 65 and 2 the support or carrier. As shown, said support or carrier consists of a perforated circular plate. The vat 1 is shown in dotted lines in Fig. 1, while the plate 2 is shown both in dotted and full lines. In dotted lines the 70 plate is shown as supported in the bottom of the vat. In full lines the plate is shown as being removed from the vat. The plate 2 is provided with a series of eyes 3, to which is attached the lower end of the flexible connecting members—as shown, chains—four in number and designated by the reference characters 4, 5, 6, and 7. The flexible connecting members 4, 5, 6, and 7 are removably connected at their upper ends to one end of the 80 lifting member 8, the latter being provided with a hook for such purpose, as indicated at 9. The lifting member 8 forms a part of the elevating and lowering element 10, which, as shown, consists of a chain hoist. The latter 85 is suspended from a trolley 11, suspended from and traveling upon an overhead track 12.

A pair of balancing flexible members is provided for suspending as well as acting as a pivot for the support or carrier. The said 90 balancing members suspend the support or carrier on an even balance, thereby enabling the tilting of the support or carrier in either direction, so as to discharge the mass of ma-

terial from either side of the support or carrier. The balancing members, as shown, consist of a pair of chains 13 14; but it will be stated that said members may be a wire rope, 5 cable, or the like.

The balancing members 13 14 have at their lower ends hooks 15, which are adapted to engage in the openings 16, formed in the plate 2 near the edge thereof, said openings 16 being arranged diametrically opposite each other. As shown, the upper ends of the flexible members 13 14 are attached to the hooks 17, carried by the frame of the trolley 11; but it will be stated that the upper ends of 15 the flexible members 13 14 can be connected at other points and yet perform their function. For example, they may be suspended from the ceiling or rafter at the point where the load is to be dumped.

20 The operation of the apparatus is as follows: After the mass of material has been dyed the connecting members 4, 5, 6, and 7 are attached to the hook 9. The elevating and lowering element is then operated, which elevates 25 the support or carrier 2 until it clears the vat 1. The support or carrier, with the material thereon, is then run or transported to any desired point through the medium of the trolley 11 and track 12. When it is desired 30 to dump the mass of material off the support or carrier, the balancing members 13 14 are then connected at their lower ends to the support or carrier 2. The elevating and lowering element is then operated to lower the support or carrier 2 until the strain or weight of 35 said support or carrier and mass of material is on the balancing members 13 14. It will then be seen that the support or carrier 2 being evenly balanced can be tilted or tipped in either direction, thereby removing the dyed 40 material. Before the support is tilted or tipped in one direction the upper ends of the connecting members 4 5 are removed from the hook 9. If the support or carrier is tilted in 45 the opposite direction, the upper ends of the connecting members 6 7 are detached from the hook 9. After the material has been dumped from the support or carrier the pair of connecting members which has been detached 50 from the hook 9 is then attached to said hook and the elevating and lowering element is then operated to raise the support or carrier, which causes a slack in the balancing

members 13 14. These latter members are then detached from the support or carrier 2 55 and the latter brought into position again for another dyeing and removal of another mass of material.

It is thought the many advantages of a hoisting apparatus constructed in accordance with 60 the foregoing description, taken in connection with the accompanying drawings, can be thoroughly understood, and it will furthermore be evident that changes, variations, and modifications can be resorted to without departing 65 from the spirit of the invention or sacrificing any of its advantages, and I therefore do not wish to restrict myself to the details of construction hereinbefore described and as shown in the accompanying drawings, but reserve 70 the right to make such changes, variations, and modifications as come properly within the scope of the protection prayed.

Having thus fully described my invention, what I claim as new, and desire to secure by 75 Letters Patent, is—

1. A hoisting apparatus involving a track, a trolley suspended therefrom and traveling thereon, an elevating and lowering element suspended from the trolley, a carrier detachably connected with said element and capable of being tilted in opposite directions, and a pair of balancing members connected at one end to said trolley and at their other ends detachably connected to said carrier, to permit 85 of the tilting thereof in opposite directions.

2. A hoisting apparatus involving a traveling member, an elevating and lowering element suspended from said member, a carrier plate detachably connected with said element 90 and provided with a pair of diametrically opposite openings, said plate capable of being tilted in opposite directions, and a pair of balancing members having their upper ends secured to a suitable support and their lower 95 ends engaging in said openings, said balancing members adapted to suspend and act as a pivot for said plate when tilting the same in opposite directions.

In testimony whereof I have hereunto set 100 my hand in presence of two subscribing witnesses.

JAMES A. WILLARD.
